DATA REPRODUCING MACHINE

Arthur H. Dickinson, Scarsdale, and Robert I. Roth, Valley Stream, N. Y., assignors to International Business Machines Corp., New York, N. Y., a corporation of New York

Application June 16, 1939, Serial No. 279,505

13 Claims. (Cl. 164—115)

This invention relates to a data reproducing machine and more particularly to a machine capable of reproducing coded data representations from one type of carrying medium to another and different type of carrying medium. The present invention is an improvement of applicants' co-pending application Serial No. 275,503 filed June 16, 1939.

The data carrying mediums may be of the types, or forms, suitably adapted for the automatic control of well-known types of machines, such as, statistical machines, typewriting machines, or the like. For example, in mechanized accounting systems, employing various types of known statistical machines, record cards, having data representations disposed thereon, are used for controlling the operations of the machines used in such systems; when utilizing the well-known Hollerith type of statistical card, the data representations usually are in the forms of perforations, which are formed at different columnar index point positions. The codes employed may be of different types, such as the combinational perforation code system, or single perforation code system.

It has been suggested to employ different types of control records other than the perforated record cards, for controlling the machines referred to, for example, one type suggested being a record medium having a layer of light sensitive emulsion disposed thereon which, when exposed to suitable recording mechanisms, and properly conditioned, is adapted to bear the data representations in the form of imperforate control spots disposed in various code positions thereon. These control spots, or index points, may then serve as light modifying or modulating areas for controlling the statistical or other operations of the machines.

It has been found that, when it is desired to employ such machines controlled by different types of control records provision must be made, whereby the data representations carried by one type of records can be reproduced, and formed on the other type of records, or vice versa. To simplify the description to follow, the illustration and disclosure thereof, will be limited to suitable mechanism which may be conditioned, whereby the data representations, in the form of coded perforations, on a record control card, can be reproduced on a photographic control record, in the form of differentially positioned control spots, or vice versa. These features broadly are shown and claimed in the said co-pending application.

In addition to the described features, the present invention proposes the provision of additional control mechanism, whereby a plurality of record recording operations may be effected, in accordance with the data disposed on a single record

medium. For example, it may be desired to record the data other than the control number of repeat operations, which is disposed on one type of record medium (record card), a plurality of times upon another type of record medium (photographic film record). In such cases, whenever the machine is conditioned to reproduce a plurality of film frames from each record card, and in accordance with the data disposed thereon, each record card is considered a master card, and each record may have a control number disposed thereon, in a certain field, indicating the number of film frames that are to be reproduced from it. In these cases, the number of film frames reproduced from each card will be in accordance with the number disposed thereon.

Specifically, one method, of effecting such operations, will be shown to comprise sensing the control number, indicating the number of film frames to be reproduced, and storing this number in suitable means, such as stepping relays, which in turn, control the reproduction of the number of film frames accordingly. Upon sensing the data to be reproduced, this data is recorded upon the first film frame, and simultaneously entered into storing devices, such as stepping relays. Card feeding operations are now discontinued, until the data from the card has been reproduced on the film frames, the number of film frames being determined by the control number on the card. During this reproducing operation, the data reproduced is obtained from the storage devices. Each film frame is counted, as it is reproduced, and, when the predetermined number has been reproduced, control elements are called into operation to discontinue further recording operations momentarily, clear the settings of the storing devices, and cause a new record card to be presented to the machine for reproducing other film frames, in accordance with the data disposed on the new record card, in the manner just outlined.

The machine can also be conditioned to reproduce the data, sensed from the individual frames of the photographic film record, upon any desired number of record cards. The steps to effect this type of recording are similar to the ones outlined in connection with film recording from the record cards, and need not be repeated at this time.

One of the objects of the present invention, therefore, resides in the provision of control means for controlling a predetermined number of data reproducing operations upon one type of record medium, in accordance with the data sensed on another type of record medium.

Another object of the present invention resides in the provision of means for reproducing a number of records, in accordance with the data disposed on a single record, the number of rec-

GENERAL DESCRIPTION

ords to be reproduced indicated, and determined by the said single record, the said reproduced record differing in type from the said single record.

Another object of the present invention resides 5 in the provision of means, whereby a number of records are reproduced from a single record, and storing, electrically, the data to be reproduced for controlling the data reproduction operations.

Another object of this invention is to provide 10 means for sensing the number of records to be reproduced, in accordance with predetermined data, storing the sensed number, and counting the number of reproducing operations, so as to cease the reproducing operations when that number 15 equals the number sensed and stored.

Another object of this invention is to provide means for sensing and storing the number of records to be reproduced, sensing and storing the data to be reproduced, reproducing a number 20 of records, in accordance with the data stored, until the predetermined number of records are reproduced, and then automatically discontinuing reproducing operations, wiping out all the stored data, and presenting a new control record 25 to the machine to be sensed, and repeating the reproduction operations in accordance with the data disposed thereon.

Another object is to provide a device, whereby 30 the data, sensed on record cards, can be reproduced a predetermined number of times upon a photographic film record and vice-versa.

Other objects of the instant invention reside in any novel feature of construction or operation 35 or novel combination of parts present in the embodiment of the invention described and shown in the accompanying drawings whether within or without the scope of the appended claims and irrespective of other specific statements as to the scope of the invention contained herein.

Briefly and broadly, the instant application discloses, by way of illustration, record card sensing and recording means, photographic film sensing and recording means, and associated control elements, all of which, when suitably conditioned render the device effective, (1) for sensing the data representations, in the form of perforations on the record card, and thereafter, 5 controlling the film recording means, at differential times, thereby reproducing the sensed data representations on the photographic film, in the form of discrete control spots in different index point positions, (2) for sensing the differentially positioned control spots on the photographic film to control the record card perforating, or recording means, at differential times, thus reproducing the data representations sensed on the record cards in the form of differentially 10 displaced perforations, or the like, and (3) for effecting reproduction of one type of record medium, a predetermined number of times, in accordance with the data disposed on the other type of record medium.

20 Referring now to Fig. 1, the data reproducing mechanism, or device, is shown to comprise a record card magazine, or supply hopper M, from which the cards are fed, singly, by the card feeding means, comprising in part, the card picker 41 and 48 and actuating arm 46 therefor, to the feed rollers 80 to 83 past the card sensing station, including the brushes 116, to the card drum 120, feed rollers 122 and 123, and card stacking magazine, or hopper N. Interposed between the pairs of feed rollers 80, 81 and 82, 83 is shown a suitable type of card recording means, for example, the punch plungers 65 and control magnets 66 therefor, and an additional card sensing station including the brushes 112.

25 The photographic film 180 is fed, by means of the driving sprockets 213, from a supply reel 200 past a suitable sensing and recording station, comprising the individual light sources 175, associated light conducting quartz rods 177 and 182, and suitable light responsive means, such as photo-cells 183, and an additional sensing station, comprising light source 186, quartz rods 188, 189, and photo-cells 190, to a suitably disposed take-up reel 201.

30 Suitable control and conditioning means are provided, so that the control units referred to can be conditioned, whereby the cards are fed, singly, from the supply magazine to the card sensing station. At the card sensing station, the perforations on the record cards are sensed, at differential times, for controlling the energization of the corresponding individual light sources, at the said differential times, for effecting the recording of the control spots on the photographic film. The mentioned control units can also be 35 conditioned, so that the control spots on the photographic film are sensed, at differential times, for controlling the operation of the associated photo-cells, which photo-cells in turn, are effective to control the card perforating control magnets, thereby effecting perforation of the record cards, in accordance with the data sensed.

40 Further control means are provided, whereby a predetermined number of film frames are reproduced, in accordance with the data disposed on a single record card, or vice versa, and in addition thereto, automatically discontinuing the reproducing operations, when a predetermined 45 number of records have been reproduced, and 50 55 60 65 70 75

conditioning the machine, for further automatic reproduction operations, in accordance with the data disposed on other records.

By referring to Figs. 7 and 8, facsimiles of portions of the perforated record cards and recorded photographic film are shown. In Fig. 7, the reference character 53 represents the differentially disposed perforations on the record card 52, whereas in Fig. 8, the reference character 181 represents the differentially disposed control spots, or light modifying areas, on the control film record 180.

Record card feeding means

Referring now to Figs. 1 to 4, it will be shown, how the card feed magnets 20 control the operation of the record card feeding means. A motor 21 (Fig. 12a), suitably mounted in the machine, is effective to rotate the shaft 24, by means of the interconnecting belt 22, pulley 23, pawl 25 secured to said pulley, and ratchet 28 which is secured to shaft 24, and engaged by the pawl 25. In this manner, the shaft 24 is rotated continuously as long as the motor is operated. Gear 27, attached to the shaft 24, is effective to drive gears 28 and 29, by means of the interconnecting gears 30 and 31, both of which are affixed securely to shaft 32. Gear 29 is secured to shaft 33, thus it is seen, that shafts 32 and 33 are arranged to be rotated continuously, similarly as shaft 24, as long as the motor is operated. A single tooth ratchet 35 is adapted to be secured to gear 28, both gear and ratchet being rotatably mounted on the supporting shaft 34, and to which shaft an arm 36 is attached. A spring actuated dog 37 is pivotally mounted on the arm 36, and arranged to be held out of engagement with the ratchet 35, by the armature 38 associated with, and controlled by the magnets 20. From the description thus far, it is understood, that upon energization of the magnet 20, the associated armature 38 is displaced, sufficiently out of the path of dog 37 and arm 36, to release these elements, and permit the dog 37 to engage the single tooth of ratchet 35, thus effecting rotation of the shaft 34, by means of the ratchet and associated gearing. Shaft 34 is rotated, as long as the magnet 20 remains energized, and in turn, effects rotation of gear 39 attached thereto, gear 40 and shaft 41 to which the last mentioned gear is secured.

Complementary cams 42 and 43 (see Fig. 5) are mounted on shaft 34, and are arranged to displace the two armed lever 44 on shaft 45, thereby rocking shaft 45 and the sector arms 46 (Fig. 1) attached thereto. The said sector arms are provided with gear teeth which mesh with racks on the card picker slides 47. A knife edge 48, attached to the slides, is adapted to engage the bottom card in the supply magazine, or hopper M, and displace the card to the right (Fig. 1), when the picker slide is reciprocated by the cams 42 and 43 on shaft 34. The ratio of the described gearing is such that gear 28 rotates one revolution for each card cycle. Associated with the card hopper M are the contacts 54 (Fig. 1a) controlled by the lever 55, which contacts are adapted to remain closed, as long as cards are provided in the supply hopper, and upon exhaustion thereof the said lever is permitted to swing in a clockwise direction to open the said contacts.

Upon deenergization of the magnet 20, the spring-urged armature 38 is positioned in the path of dog 37 and arm 36, so that disengagement of dog 37 and ratchet 35 is effected. A locking lever 49 is provided to maintain arm 36 in

a predetermined position, thus locking the shafts 34 and 41 in the normal "D", or home position (see Fig. 10).

It should be mentioned, that cam elements 50, 153 and 157 are provided, on the shaft 41 (Figs. 5 and 2a) to control the associated cam controlled contacts P-1 to P-12, 154 and 158, respectively (see Figs. 12a to 12d), and, that shaft 33 carries cam elements 51 to control the associated cam controlled contacts C-1 to C-11. Upon shaft 33 (see Fig. 4), additional suitable cams 56 and 161 (see Fig. 12c) are mounted, which are adapted to operate the associated contacts 57 and 162, at different times, during the machine cycle (see Fig. 10), and in addition thereto, the brush 58 of a well-known type of impulse emitter 59 (see Fig. 12c) are secured to the said shaft, so that the individual conducting segments 60 are connected to the common conducting ring 61, at different times, during the machine cycle by means of the rotated brushes, the purpose of which will be described later.

It has now been shown, how the record cards 52 are fed singly from the supply hopper M, by means of the card picker mechanism, whenever the control magnet 20 is energized. For further detailed description of the card feeding mechanism U. S. Reissue Patent #21,133, dated June 27, 1939, shown in detail. The individual record cards are now displaced and fed to the first set of feed rolls 80 and 81, which in turn, feed the cards past the card recording or perforating station. It will be shown, that the individual cards are positioned intermittently, by the feed rollers, past the card recording station and the card sensing stations. This mechanism will now be described in conjunction with the card recording or perforating means.

Record card recording means

Referring now to Fig. 1, the card recording station is shown to comprise recording means, illustrated in the form of record card perforating plungers 65, the operation of which, are selectively controlled by the magnets 66. The said magnets, upon energization, select the associated plungers so that, during the operation of the operating bar 67, the bar depresses or operates all the selected plungers, and thereby effects perforation of the record card. This operation is explained in detail, in the patent referred to hereinabove, and therefore the following brief description thereof is deemed sufficient. It is well known, that an individual plunger 65 and controlling magnet 66 are provided for each columnar area of the card, and that all the selected plungers are operated or depressed for all columnar areas simultaneously. It will be explained shortly, how the different index point positions of the cards are fed, intermittently, to the punching station, and that the perforating thereof is effected while the cards are stationary therat.

The said plungers are shown provided with individual spring-urged pivoted interposer pawls 68, 65 which are connected to the armatures 69 of the magnets, by call wires 70, so that, upon energization of a magnet, the connecting call wire is effective to swing the pawl 68 to the right, as viewed in Fig. 1, positioning the said pawl in the path of the operating bar 67. Upon depression of the said bar, which is adapted to cooperate with the notch 68a in the pawl, the related pawl is caused to be depressed to perforate the record card accordingly, and is then quickly withdrawn 75

therefrom to permit feeding of the card to the next index point position.

- The operating bar 67 is supported by a control ball 71 which is suitably pivoted on studs 72. 5 The control ball is attached to arm 73, by means of an adjustable turnbuckle connection 74, said arm 73 being secured to shaft 75 which is also provided with an arm 76. An eccentric 77 is suitably disposed and formed on the shaft 24, 10 which eccentric is encircled by an arm 78, the upper end of which is pivotally connected to the said arm 76.

It is now seen that, since the eccentric 77 is positioned on the constantly rotating shaft 24, 15 shaft 75 and arm 73 are rocked to depress, at periodic intervals, the bail 71 and bar 67. As the said ball and bar are reciprocated, any of the pawls may be positioned by the call wires so as to effect engagement of the pawls and bar. Then, 20 the connected pawls and plungers are depressed to perforate the card, and thereafter withdrawn immediately therefrom to permit the feeding of the card. Referring to Fig. 7, a facsimile of a portion of a perforated record card 52 is shown, 25 the index point positions for several columnar areas are shown to be provided with perforations 53 at, different positions in the columnar areas, to represent different data representations.

The feeding of the cards to, and from, the 30 punching station is effected by the feed rollers 80, 81, 82 and 83. The cards are fed, intermittently, by rollers 80 and 81 between a stripper plate 84 and die plate 85, through which plates the plungers are adapted to be positioned.

35 The mechanism for operating the said feed rollers is as follows—referring now to Figs. 5 and 6, it is seen, that the continuously rotated gear 27 (also see Fig. 2) is provided with a Geneva roller 86 and segment 87, which cooperate 40 with a Geneva disc 88 fixed on shaft 89. The Geneva disc is provided with seven radial slots, so that one revolution of gear 27 will rotate the shaft 89, one-seventh of a revolution, which partial revolution corresponds to a movement of 45 one cycle point of the record card. Shaft 89 rotates continuously, with an intermittent motion, as long as the motor 21 is operated. Rotatably mounted on the shaft 89 is a gear 90, which has affixed thereto a single tooth ratchet 91, and 50 secured to the shaft 89 is an arm 92, upon which a spring-urged dog 93 is pivoted. The spring-urged dog normally tends to engage the ratchet 91, however, disengagement of the dog and ratchet is effected, by the lever 94 and attached roller 55 95, which roller as shown in Figure 5, engages the tail of the dog to position it, so as to prevent engagement thereof with the ratchet. When the said lever and roller are positioned to the right, as viewed in Fig. 5, and out of the path 60 of the dog, the dog and ratchet are permitted to be engaged, thereby effecting rotation of gear 90 which is arranged to drive gears 96 and 97, which gears are fixed to shafts 98 and 99, respectively. Suitably disposed on shafts 98 and 99 65 (see Figs. 1 and 2) are gears 100 and 101 arranged to engage gears 102 and 103, which are pinned to shafts 104 and 105, respectively. Shafts 98 and 104 carry the first pair of feed rollers 80 and 81, respectively, whereas, the second pair of rollers 82 and 83 are carried by shafts 99 and 105, respectively.

70 It is evident now, that whenever the lever 94 is displaced out of the path of dog 93, engagement of the dog and ratchet 91 is effected to 75 drive the feed rollers 80 to 83, intermittently,

by means of the described gearing. As mentioned hereinabove, the gear ratio is such, that for each movement of shaft 89, the feed rollers are rotated to an extent sufficient to displace the card one cycle point, which displacement is equivalent to the distance between index point positions on the record card. The lever 94 is displaced, so as to release the dog 93, by the complementary cams 106 and 107 positioned on shaft 34, which cams are engaged by the rollers 108 and 109 carried by the horizontal portion of lever 94. It is remembered, that the rotation of shaft 34 is controlled by the magnet 20, and that, whenever this magnet is energized, shaft 34 is rotated continuously by the shaft 24 and associated gearing, described hereinabove. The cams 106 and 107 are designed, so that, if the magnet 20 is not energized and the shaft 34 is not rotated, lever 94 is positioned in the path of the dog 93, thereby preventing the dog from engaging the driving ratchet 91. However, should the said magnet be energized, cams 106 and 107 are turned, lever 94 displaced, permitting engagement of the said dog and ratchet, and establishing a driving connection between the intermittently driven shaft 89 and gear 90 for effecting intermittent movement of the card feed rollers 80 to 83.

Adjacent to rollers 80 and 81 is suitably disposed a control lever 111, which lever is effective 30 to close contacts 110 (see Figs. 1a, 1b, and 12), as long as cards are fed successively to, and from, the rollers 80 and 81, however, when cards are not fed successively thereto, the said contacts are opened. 35

Record card sensing means

Referring now to Fig. 1, the record cards are fed from the recording station to a sensing station, by the rollers 82 and 83, through the guide plates 115, and past the suitably mounted sensing brushes 116 (also see Fig. 12c), cooperating with the conducting roller 117. It is understood, that the index point positions of the intermittently fed cards are positioned properly at the sensing station, so that, whenever perforations 45 are present in the cards at particular index point positions, the corresponding sensing brushes are adapted to extend therethrough and engage the conducting roller, thereby completing the circuits associated with said brushes and roller. The controlling circuits thus established will be described later herein. A facsimile of a portion of a suitable perforated record card 52 is shown in Fig. 7 provided with the differentially positioned perforations 53. 55

It should be mentioned, that at this sensing station a suitable and a well known type of card lever 118 (see Fig. 1c) is provided for controlling the associated card lever contacts 119. Whenever a card is fed to, and present at the sensing station, the said card lever is operated by the cards to close the card lever contacts, and whenever no cards are present to engage the card lever, the card lever contacts are opened. 60

In addition to the described data sensing station, an additional sensing station is provided, comprising brushes 112 (see also Figs. 1d and 12c) and conducting plate 113, which are disposed adjacent to the feed rollers 80 and 81. 65 This sensing station is provided to sense the control data disposed on the cards, and is employed whenever a predetermined number of record reproducing operations is to be effected. The brushes 112 are carried in a holding frame 114, 70 75

which may be selectively positioned on the supporting bar 63, so that the control data in any desired fields of the record cards can be sensed, and, due to the disposition of these brushes with respect to the amount data sensing brushes 116, the control data on a card, presented at the said additional sensing station, is sensed, prior to the sensing of the amount data (data to be reproduced) on the same card, when presented to the main sensing station. In this manner, control circuits may be controlled by the control data sensed, thus conditioning certain circuits, which at a later time, are controlled by the second sensing station. The said additional, or auxiliary sensing station (including brushes 112), in the instant application, is used solely for sensing the control data, whereas the second or main sensing station (including brushes 116) is used for sensing the data to be reproduced. This description is made at this time, so that hereafter, the card sensing stations will be referred to as the main and auxiliary card sensing stations.

Record card stacking means

From the main sensing station, the cards are fed to a hopper N (Fig. 1), by means of the card stacker drum 120, and associated feed roller 121, and feed rollers 122 and 123. The said drum and feed rollers are operated continuously, with an intermittent motion, and in a synchronous relationship with the feed rollers 80 to 83.

Referring now to Figs. 2, 5 and 6, it is remembered, that shaft 89 is rotated continuously with an intermittent motion. This shaft has secured thereto gear 124, which drives gears 125 and 126, both of which gears are mounted on a common hub 127, which is rotatably supported by shaft 99. By means of the gearing, comprising the gear 128 pinned to idler shaft 129, gears 130 and 131 pinned to shaft 132, the gear 126 is effective to rotate the gear 133, and associated shaft 134, upon which is mounted the stacker drum 120 (see Fig. 1).

Pinned to the opposite end of shaft 134 is a gear, 45 not shown, but similar in size to gear 133, and which is arranged to drive gear 135 (see Fig. 2) and its related shaft 136, upon which the feed roller 121 (Fig. 1) is mounted; thus, it is seen, that the stacker drum and associated feed roller 50 are rotated continuously, with an intermittent motion, as long as the motor is energized, and in synchronism with the operation of the feed rollers 80 to 83, since the controlling drive shaft 89 is the common drive for both the controlling 55 gearings. The gear ratios between gears 124 and 133 are such, that one-seventh of a revolution of gear 124 will displace the drum upon which the cards are held, one cycle point.

Gear 130 also drives gear 137 and related shaft 60 138, upon which shaft is mounted gear 139, which drives the gearing comprising gears 140 and 141 pinned to shaft 142, gears 143 and 144, the latter gear being pinned to shaft 145. Upon the shaft 142, a feed roller 123 (Fig. 1) is mounted, and by 65 means of a gear similar to gear 141, mounted on the shaft 142, the gear 146 and related shaft 147 are driven; feed roller 122 is mounted on shaft 147 and rotated thereby.

From the feed rollers 122 and 123 (Fig. 1), the 70 cards are stacked in the hopper N, whereat provision is made to insure proper insertion of the cards in the stack, by providing a rubber stacker roll 148 mounted on shaft 145, which when rotated, by means of the said shaft, urges the cards 75 to the right, as viewed in Fig. 1.

Referring now to Fig. 9, the stacker drum 120, mounted on and rotated by shaft 134, is shown to be provided with a plurality of pivoted gripping fingers 149. These fingers are urged into card gripping position by the spring pressed 5 plungers 150. Fixed face cams 151 are provided to be suitably disposed so as to cooperate with the fingers, to effect their opening and closing at the proper time. The timing of the fingers is such that the record card is gripped, after it 10 passes the feed roller 121, and held securely to the drum as it rotates to further advance the card, and finally releasing and discharging it to the feed rollers 122 and 123.

Film sensing and recording means

15

With reference to Fig. 1, one of the film sensing means is shown to comprise generally, a light source comprising the individual lamps 175 supported in suitable enclosures, generally indicated 20 176, from one side of which individual light conducting quartz rods 177 are provided, and which are supported by the frame member 184. Mounted in the same plane as member 184 is another member 178 for supporting the quartz rods 182 25 extending to individual light responsive means 183, such as photocells. The said members 178 and 184 are provided with a small gap between them through which the photographic film 180 is fed. In the instant application, the film is fed 30 intermittently to, and from, the sensing station, by means to be described later herein, so that the index point positions of the film are presented successively thereto.

Referring to Fig. 8, a facsimile of a portion of 35 the film record 180 is shown wherein the index points 181 are shown differentially disposed in various index point positions in the columnar areas. The quartz rods 177 and 182 are spaced in the respective members 184 and 178 so that they 40 correspond to the individual columnar areas in position.

The method of sensing the data representations on the photographic film record will now be understood, assuming that the index points, representing the data representations, in the form of control spots are presented, intermittently, and successively to the sensing position or station, and that the individual light sources 175 are continuously energized, it is seen that, when no control spots appear at the particular index point positions analyzed, the light conducted from the light source to the film record by the one group of quartz rods is permitted to permeate the film, and be conducted by the other group of quartz rods to the related photo-cells, thereby conditioning the photo-cells in a predetermined manner. However, whenever control spots appear at the sensing position, the corresponding beams of light conducted thereto are modified or blocked 50 off, so that the light no longer is conducted to, and impinged upon, the related photo-cells, thereby controlling the action or operation of the photo-cells. It is obvious, since the said control spots disposed on the film record in different index point positions, and since the index point positions are analyzed successively, that the different beams of light are modified, at differential times, for controlling the operation of the related 55 light responsive means.

The method of recording the data representation in the form of differentially positioned control spots is now evident, since the only requirement necessary for this operation is for the light sources to be normally deenergized. Now, as the 70 75

film record is fed to the sensing station intermittently, the individual light sources are controlled, so as to be energized at different times, thus permitting the beams of light to be conducted and directed by the quartz rods 177, to the corresponding columnar areas, thereby effecting recording upon the light sensitive photographic film, at different positions, in the said columnar areas corresponding to the timed intervals at which the related light sources are energized.

In addition thereto, another film sensing station is provided, comprising an elongated light source 186 disposed in a suitable housing 187, which may be an integral part of the member 184, and a plurality of individual light conducting elements 188, such as quartz rods similar to the rods 177, which are disposed in the member 184. Correspondingly positioned quartz rods 189 are provided in member 178 for conducting the light rays to individual photocells 190. It is seen, that the rods 188 and 189 are positioned, so that the control spots on the film record 180 are effective to modify the light rays conducted to photocells 190, before the said spots are effective to modify the light rays conducted to photocells 183 by the rods 177 and 182. The purpose of this arrangement is, so that the control data disposed on the film record can be sensed at the first sensing station, prior to the sensing of the amount data on the film record, at the second sensing station. To simplify the description to follow, the first sensing station for sensing the control data on the film will be termed the auxiliary film sensing station, whereas, the second sensing station for sensing the amount data will be referred to as the main film sensing station.

Film feeding means

Referring now to Figs. 1, 2 and 4, the means for feeding the photographic film from the supply reel 200 intermittently to, and from, the sensing or recording station, and to the take up reel 201 comprise the following gearing, which gearing is controlled by the shaft 142, which as described hereinbefore, is rotated continuously with an intermittent motion. A gear 202, pinned to shaft 142, is arranged to drive the gear 203 rotatably mounted on shaft 204; attached to gear 203 is the single tooth ratchet 205, which is arranged to cooperate with the dog 206 pivotally mounted on the arm 207, which arm is fixed to the shaft 204. The armature 208 of magnet 209 normally, when the magnet is deenergized, is adapted to be positioned in the path of the said arm and dog, thereby presenting engagement of the dog 206 and ratchet 205. However, upon energization of the said magnet the armature is displaced sufficiently to release the dog, thereby permitting engagement of the said dog and ratchet, thus effecting rotation of shaft 204 by means of gears 202 and 203.

Secured to shaft 204 is the gear 210 engaging gear 211, which is fastened to shaft 212, upon shaft 212 which is mounted the film drive sprocket 213. Also secured to shaft 212 is a pulley 214 which, by the connecting belt 215, is adapted to rotate the shaft 216, upon which the take up reel 201 is mounted. Thus, it is seen, that the film 180 is fed to, and from, the sensing and recording stations, intermittently, by means of the driving sprocket 213 and the described gearing. It should be mentioned, that contacts 218 are provided, and adapted to be closed by the lever 219, whenever the film record 180 is present in

the sensing unit, and are arranged to be opened whenever the film record supply is exhausted.

Certain circuit controlling elements are provided, which will now be described, and which must be operated, in synchronism, with the feeding of the film, but are shown operated with a uniform motion instead of an intermittent motion, therefore, the following controlling and gearing means is provided. Referring particularly to Fig. 4, it is seen, that the continuously rotated gear 28 has secured thereto, an additional single tooth ratchet 220, which is arranged to cooperate with a dog 221 pivotally mounted on the arm 222, which arm is secured to a gear 223 rotatably mounted on shaft 34. Normally, the dog and ratchet are maintained disengaged, by means of the armature 224 of magnet 225, in a manner similarly as described hereinabove with reference to the same type of clutch. Upon energization of the magnet, the armature 224 releases the dog 221 to engage the ratchet 220, thus effecting rotation of gear 223 and the gear 226 engaged thereby (Fig. 2). Gear 226 is secured to shaft 227, which carries the series of cams 228, for controlling the associated contacts F (see Figs. 12a to 12c). In addition thereto, cams 155 and 159 (see Figs. 12b and 12c) are secured, to shaft 227 to operate the associated contacts 156 and 160, respectively, at predetermined times (see Fig. 10), for conditioning the associated circuits, the purpose of which will be understood as the description progresses.

Stepping relay means

Referring now to Fig. 11, one suitable type of stepping relay means SR is shown to comprise an advancing magnet MA, and a resetting magnet MR. Secured to the armature 163, of the advancing magnet, is an elongated pawl 164 cooperating with the ratchet wheel 165, which is freely mounted on the stud 166. Upon energization of the advancing magnet MA, the pawl is positioned to the next adjacent tooth of the ratchet, so that, upon deenergization thereof, the ratchet wheel is advanced, or partially rotated, to the left, as viewed in Fig. 11, by means of pawl 164 and the spring 167. A suitable conducting arm SA is provided, which is secured to the suitably insulated member 168, which in turn is fixed to the ratchet wheel. Thus, it is seen, that upon advancement of the ratchet wheel, the arm SA is advanced to engage the next contact of the group of contacts CT. To reset the arm SA to the normal position shown, namely, in a position so that the arm engages the first contact of the group of contacts CT, magnet MR is energized to attract its armature 169, thus displacing the extension 170 of the armature, from the ratchet 165 (which normally acts as a locking pawl) sufficiently, to engage the pawl 164, and dispose it from the ratchet, so as to free the ratchet wheel, thereby permitting the arm SA and ratchet 165 to be returned to the normal setting shown, by means of the spring 171.

It is understood, that any number of contacts CT can be provided to be engaged successively by the stepping arm SA. For example, when the stepping relay means is used as a data storage device, ten digital contacts are provided, as shown in Figs. 12b and 12c for the relays indicated SR1u to SR4u, SR1t to SR4t, SR8 and SR9.

In certain instances, it is desired to energize the reset magnet, upon reception of an advance impulse, when the stepping arm SA engages the last contact in the group of contacts CT. In

such cases, provision of control contacts TC is made. Whenever the arm SA is first advanced, from the normal position as shown, a double armed member 172 is provided to follow the advancement of the said arm. The said member is loosely mounted on the stud 166, and normally is held in the position shown, by means of the member 168 to which the arm SA is secured. However, upon advancement of arm SA and member 168, the spring 173 is effective to advance the member 172, so that the longer arm of the member 172 is moved out of engagement with the spring pressed latch 174, permitting the said latch to rest upon one of the spring blades of the contacts TC. The contacts TC are disposed so that, when the arm SA engages the last contact of the group of contacts CT, and when the advance magnet MA is operated to advance the arm SA farther to the left, as viewed in Fig. 11, the member 168 is effective to engage one of the spring blades of contacts TC, to close the said contacts, and permit the latch 174 to lock the contacts TC in the operated position. During the description of the circuit diagram, it will be pointed out, how a control circuit to the reset magnet MR may be controlled, by the latched contacts TC, to effect resetting of the stepping arm SA and member 168 to the normal position shown in Fig. 11. Upon resetting of the said arm and member, member 172 is restored to normal position, as shown, to restore the latch 174, thereby permitting the contacts TC to be opened.

Operation of machine

Referring now to the circuit diagrams, particularly Figs. 12a, 12b, and 12c and arranged in the order named, the operation of the data reproducing machine will be described. The description to be given first will relate to sensing the perforated card, and reproducing the data representations sensed upon an unrecorded photographic film record, in the form of differentially positioned control spots. To effect this type of data reproduction, the machine must be conditioned accordingly, therefore, let it be assumed, that the main switch MS is closed, that the control switches S1 to S17 are positioned in the CF positions as shown, that perforated record cards are provided in the supply hopper N, that the unrecorded photographic film 180 is properly inserted in the machine, and that the start key is depressed to close the associated contacts SK1.

A circuit is then completed from conductor 250, to coils of relays R1, R2, contacts SK1, and contacts SK2 of the stop key to the conductor 251, causing the said relays to be energized. Upon energization of relay R1, the contacts R1a are closed to complete a circuit from the power supply source to the drive motor 21, thereby effecting operation thereof, to drive the associated gearing described hereinabove. Upon energization of relay R2, a holding circuit therefor is established, by the associated contacts R2a now closed, through the normally closed cam operated contacts C2. The contacts R2b are also closed, upon energization of relay R2, to effect energization of card feed control magnet 20, by the circuit completed by the said contacts which is as follows: conductor 250, coils of magnet 20, switch S1, contacts R12b and R2b and the normally closed cam operated contacts C1 to conductor 251.

Upon energization of magnet 20, the shaft 34 is rotated to operate the card picker mechanism, thereby effecting the feeding of a card to the feed rollers 80 and 81. The gearing driving the

feed rollers is also operated, when magnet 20 is energized and shaft 34 is operated. Thus, the record card is fed intermittently, past the auxiliary sensing station, and up to the card perforating station, and thereby causes the contacts 110 to be closed. A circuit is then completed, during this machine cycle, from the power supply conductors 250 and 251 to the coil of relay R3, energizing said relay, and causing the associated contacts to be closed. The P2 cam contacts are closed, at the same time, the contacts 110 are operated, thus a circuit is established from conductor 250 to the coil of relay R9, contacts R3c, switch S4, and contacts P2 to conductor 251, energizing the said relay. A holding circuit for this relay is completed, upon closure of the associated contacts R9a, through the switch S5, and cam contacts P3 which are closed at the same time contacts 110 are closed, and are maintained in this condition the remaining part 20 of the machine cycle (see timing chart, Fig. 10). This condition occurs near the end of each machine cycle, so it is understood that relay R9 is energized, near the end of each machine cycle, and maintained so until after the beginning of 25 the following machine cycle.

The purpose, of the circuit arrangement shown in Fig. 12a is, to cause operation of the relays R3, R4, R1, R8, and R9 so that the contacts R3a, R4a, R1a, R8a and R9b, which are connected in series with the contacts R2a, are all closed at one time in the cycle, and thus provide a bridge circuit for the circuit, including the cam contacts C2 (which are opened near the end of each machine cycle), so that relays R1 and R2 are maintained energized, thus providing continuous operation of the machine.

However, when first starting the machine, it will be necessary to hold the starting key depressed, for several machine cycles, until all the control circuits are properly conditioned for continuous operation. This is obvious, since at the end of the first machine cycle, the first card is just approaching the card perforating station, this being the case, it is seen, that contacts 119 45 at the card sensing station are still open, thus preventing operation of relay R4, and thus preventing continuous operation of the machine at this point.

Assume that the start key is kept depressed, so 50 that another machine cycle is completed, the feed rollers 82 and 83 are then effective to feed the first card up to the second or main sensing station, past the card lever 118 sufficiently to close the contacts 119, but not under the sensing 55 brushes thereat as yet. The sensing operation at the main sensing station of the first card occurs during the third machine cycle. Now, at the end of the second cycle, the following circuits at this point are conditioned; Relays R3 and R4 are 60 energized, since contacts 110 and 119, respectively, are closed. Relays R7 and R8 are energized, since contacts 54 and 218 respectively are closed, these contacts are controlled by the supply of cards in the hopper M, and the film record 180 65 in the machine.

It is seen now, that at the time in the second machine cycle, the cam contacts C2 are opened, that cam contacts P3 are closed. It was mentioned hereinabove, that shortly before contacts 70 P3 are closed, the cam contacts P2 are operated to energize the relay R9, thus closing the associated contacts R9a, at this time in the cycle, so that a holding circuit therethrough is established for the said relay, by means of the operated con- 75

tacts P3; and as mentioned before, this holding circuit is maintained for the remaining part of the said cycle, and during the beginning of the following machine cycle. Thus it is seen, that 5 from now on, during each machine cycle, a circuit is completed from conductor 250 to coil, of relays R1 and R2, contacts R2a, R8a, R4a, R7a, R3a, R9b, switch S3 and normally closed contacts SK2 of the stop key to conductor 251. This circuit is completed at a time in the cycle when cam contacts C2 are opened, thus, the relays R1 and R2 are maintained energized for the beginning of each following machine cycle.

At the beginning of each machine cycle, cam 15 contacts P8 are closed momentarily; therefore, each machine cycle after the energization of relay R3 the following circuits are established: conductor 250, coil of relay R15, switch S11, contacts R3g, and contacts P8 to conductor 251, energizing relay R15, and completing a holding circuit therefor, from conductor 250, coil of relay R15, contacts R15a, switch S12, and contacts P9 to conductor 251. Since the cam contacts P9 are closed during the entire sensing cycle, relay R15 25 is maintained energized all during the sensing cycle. Through the contacts R15b and cam contacts P2, both of which are now closed, near the end of the sensing cycle, a circuit is established to energize relay R14, and establish a holding circuit therefor, through contacts R14a and contacts P3. Thus, it is seen, that relay R14 is energized near the end of each cycle, and maintained energized until the following cycle.

Also, near the end of each machine cycle, the 35 cam contacts C1 are closed, and maintained so until after the beginning of the following cycle, so that the magnet 20 is energized at the end of each cycle, thus effecting a card feeding operation for each machine cycle, whenever the 40 relay C12 is deenergized at this time in the cycle. The machine is now conditioned for automatic operation, and at the beginning of the third cycle, the card sensing operations at the main sensing station are effected. Therefore, it is evident at this time, it will be necessary 45 to render the film feeding mechanism operative, so that the film record is positioned, intermittently, in synchronism with the progression of the record card. This is effected as follows:

Near the end of each machine cycle, the cam contacts C3 are closed, therefore, a circuit is completed from conductor 250 to the coil of relay R6, contacts R4b, R9c and cam contacts C3 55 to conductor 251 energizing this relay. These circuits are maintained for the remaining part of the said cycle, and during the beginning of the following cycle, by means of cam contacts C3. Before these said cam contacts are opened, 60 during the said following cycle, contacts P1 are closed to maintain the relay R6 energized, through the associated contacts R6b all during the sensing and recording portions of each cycle.

Closure of contacts R6a completes a circuit as 65 follows, near the end of each cycle, from conductor 250 to coils of magnets 209 and 225, contacts R6a, switch S2, contacts R2b and cam contacts C1 to conductor 251, energizing said magnets. Energization of magnet 209 permits 70 the film feeding mechanism, described hereinabove, to become effective to feed the film record 180, intermittently, to its sensing and recording station, in timed relationship, with the feeding of the record cards 52 past the sensing stations. 75 Energization of magnet 225 is effective to ren-

der the control shaft 227 operative, to control the timing of the F cam contacts, which are controlled by cams 228 mounted thereon, the purpose of which will be described as the description progresses.

It was stated, that the machine is conditioned for automatic operation, near the end of the second cycle, and that card sensing operations are effected at the main sensing station during the third machine cycle. It is during the last 10 mentioned cycle that relays R12 and R13 are energized. At the beginning of each cycle, contacts P4 are closed momentarily, and, due to the previously conditioned circuits the following circuits are established: conductor 250 to coil 15 of relay R12, contacts R14b and contacts P4 to conductor 251, energizing the said relay to establish a holding circuit therefor, through the contacts R12a and normally closed contacts R16e. Contacts C5 are also provided to maintain this 20 holding circuit at certain times, due to the closure thereof, which occurs near the end of each cycle. The purpose of these contacts will be understood as the description progresses. Relay R12 will now remain energized until relay 25 R16 is energized. Energization of relay R12 causes the circuit to the card feed control magnet to be opened, due to contacts R12b, thus preventing further card feeding, and advancing operations until relay R16 is energized.

It is noted that contacts R12c are provided to bridge the contacts R6a in the film feeding control magnet 209 circuit, and contacts R12k are provided to bridge the contacts R4a, R7a, R3a and R9b in the circuit including relays R1 35 and R2. The purpose of this arrangement is to insure that, upon the feeding of a last card, the data thereof is fully reproduced before causing interruption of the automatic operations.

Before continuing with the description of the 40 energization of relay R16, the circuits which are conditioned by the control data or numbers sensed on the cards should be described. Assume now, that the first card is just being fed past the auxiliary sensing station, and that a predetermined control number is perforated in the card, indicating that a predetermined number of individual film frames are to be produced, in accordance with the amount data on the said card. Upon sensing the control data 45 or number (which are disposed in predetermined fields or columnar areas) at the auxiliary sensing station, the following circuits are completed: conductor 250 to pick-up coils a of relays R18 and R19, conductors 191, auxiliary sensing brushes 112, conducting plates 113, contacts R3j, P11 and 154 to conductor 251, energizing the said relays. Holding circuits are then completed, which are as follows: conductor 250, holding coils b of relays R18 and R19, contacts R18a and R19a respectively, conductor 181a, advancing magnets MA5u and MA5t, switch S12 and contacts P9 to conductor 251. In this manner, relays R18 and R19 are maintained energized for the entire sensing portion of the cycle. The 55 stepping arms SA5u and SA5t, of the relays SR5u and SR5t, are not advanced until the associated control magnets MA5u and MA5t are deenergized. Due to the closure of contacts R18b and R19b, at a predetermined time in the 60 sensing cycle, a plurality of impulses are now impressed upon the advancing magnets MA1u and MA1t to energize the said magnets, a number of times, corresponding to the control numbers sensed on the said card at the auxiliary sens- 65 70 75 80 85 90 95

ing station, thus entering the control data or number into the data storing devices, represented by the relays SR1u and SR1t. The control circuits for the said advancing magnets are as follows: conductor 250, coils of magnets MA1u and MA1t, contacts 1 of the group CT5u and CT5t, contacts R18b and R19b, switch S10 and contacts 158 to conductor 251. In this manner, the control number of the first card is entered in the storing devices SR1u and SR1t referred to.

Due to the spacing of the auxiliary and main sensing stations, and the difference in the timing of the sensing operations at these stations (see Fig. 10), it is necessary to provide a plurality of storing devices, for storing the different control numbers disposed on the different cards which are fed, successively, to the stations. It is sufficient to mention, that during the sensing of the second card at the auxiliary sensing station, sensing of the first card at the main sensing station is being effected. After the first card at the auxiliary station is sensed, the contacts P9 open to break the holding circuit for relays R18 and R19, and causing deenergization of magnets MA5u and MA5t, thus advancing the associated stepping arms SA5u and SA5t to the second contacts of the group CT5u and CT5t, respectively. In this manner, a second group of storing devices, namely, SR2u and SR2t, are selected for storing the control data of the second card.

During the sensing of the second card at the auxiliary sensing station, whenever the control perforations are sensed, circuits are completed through the brushes 112 to energize the pick-up coils *a* of relays R18 and R19, at predetermined times, corresponding to the positions of the perforations, which circuits were traced hereinabove. The holding circuits for these relays, as described, extend from conductor 250, through the holding coils *b* of relays R18 and R19, contacts R18a and R19a respectively, conductor 191, magnets MA5u and MA5t, switch S12 and contacts P9 to conductor 251, again energizing the said magnets. Through the contacts R18b and R19b, a number of timed impulses, corresponding in number to the sensed control data, are impressed upon the advancing magnets MA2u and MA2t of the second group of storing devices, by means of the circuits from conductor 250 to magnets MA2u and MA2t, contacts 2 of the group CT of relays SR5u and SR5t respectively, contacts R19b and R18b, switch S10 and, contacts 158 to conductor 251, thus entering the control number into the said relays, corresponding to the control number sensed, on the second card, at the auxiliary sensing station. After sensing the said second card, the relays R18, R19, magnets MA5u and MA5t are deenergized, due to the opening of contacts P9. Immediately thereupon, arms SA5u and SA5t of relays SR5u and SR5t are advanced to the third contacts of the group CT5u and CT5t to direct the impulses, initiated by contacts 158, to the advancing magnets MA3u and MA3t of a third group of storing devices, when the control number is sensed on the third card at the auxiliary sensing station.

It was mentioned, that during the sensing of the second card at the auxiliary station, the first card sensing operations are begun at the main sensing station. It will now be described, how the data sensed at the main station, which is the data to be reproduced upon the individual film frames, is stored, and thereafter effective to control the film recording operations. The first film

frame recording is controlled directly from the card at the main station, and for all the remaining frames to be reproduced, the recording operations are controlled by the stored data.

Upon sensing the amount data perforations (or data to be reproduced) at the main station, the following circuits are completed through the sensing brushes 116: conductor 250 to pick-up coils *a* of relays R20 and R21, conductor 192, brushes 116, conducting roller 117, contacts P12, parallel circuit arrangement comprising contacts R12j and R6c, contacts 57 to conductor 251, energizing the said relays. Circuits are then completed from conductor 250 to holding coil *b* of relays R20 and R21, and contacts C11 to conductor 251 to maintain the said relays energized, during the sensing operations at the main sensing station. Upon sensing the amount data perforations as described, two operations are effected simultaneously, (1) recording the sensed amount data upon the first film frame directly from the sensed record card, and (2) storing the data sensed into suitable storing devices such as relays SR8 and SR9. To effect entry of the data, in the said storing devices, the impulses initiated by the cam controlled contacts 162 are impressed upon the magnets MA8 and MA9, by the circuits from conductor 250, conductor 193, magnets MA8 and MA9, contacts R20b and R21b respectively to contacts 162 and conductor 251, causing the said magnets to be energized, a plurality of times, depending upon the time of closure of contacts R20b and R21b, thereby advancing the conducting arms SA8 and SA9 accordingly, to represent by their position the data sensed by the brushes 116.

The sensed data is reproduced upon the first film frame of the group directly from the sensed card, by means of the circuits extending from conductor 250 to switch S16, individual light sources 175, conductors 194, contacts R13h and R13j (relay R13 is energized after sensing the first card which was set forth hereinabove), brushes 116, conducting roller 117, contacts P12, R12j, R6c and 57 to conductor 251, energizing the individual light sources, at the differential times, the perforations on the card are sensed at the main station.

It was mentioned hereinabove, that upon energization of the film feed control magnets 209, the photographic film record 180 is fed, intermittently, to the recording station in synchronism with the intermittent feeding of the record card to the card sensing station so that, for example, when the "9" index point positions on the card are presented for sensing thereof, the blank film record is fed to its recording station, so that the "9" index point position thereof, of the individual frame, or portion of the film record is presented at the film recording station. Therefore, at the particular timed intervals the light sources are energized, by means of the card sensing circuits, the light sensitive record is exposed to the light rays, at such intervals, to effect recording thereon in the form of control spots, as indicated in Fig. 8, at differential positions, in accordance with the data sensed. Further explanation of this form of sensing the record cards, and recording the data in the form of control spots on the film record is deemed unnecessary.

Each film frame reproduced is counted, and the circuit controlling this operation is as follows, which is completed each machine cycle, and effective to enter a digit into the data storing

means SR4u until relay R12 is deenergized: conductor 250, magnet MA4u, contacts R12h, switch S7 and contacts F6 to conductor 251, energizing the said magnet to cause advancement of the associated conducting arm SA4u one step, upon deenergization of the magnet, thus entering a digit into the said data storing means.

It is remembered, that upon completion of the sensing operations at the main station, card feeding operations are interrupted at the end of the machine cycle, due to energization of relay R12, and operation of the contacts R12b, included the card feed magnet control circuit, and that upon completion of the said sensing operations at the main station, relay R13 is energized by means of the contacts C6 and contacts R12f. Upon energization of relay R13, the contacts R13h to R13i are opened, and contacts R13a to R13c are closed. Contacts R13a establish a holding circuit for relay R13 which is maintained until relay R12 is deenergized. Contacts R13b and R13c now connect the data storing devices SR8 and SR9, respectively, to the individual light sources 175 to reproduce an individual film frame each cycle, in accordance with the data stored in the devices, until the number of frames reproduced correspond to the number indicated on the card, and stored in the relays SR1u and SR1t. The reproducing circuits are now as follows: conductor 250, switch S16, light sources 175, conductors 195, contacts R13b and R13c, conducting arms SA8 and SA9 respectively, contacts CT8 and CT9 respectively, conducting segments 60 of the emitter device 59, brush 58, common conductor 61, switch S13, contacts F11, conductor 196 to contacts 57, and conductor 251, energizing the individual light sources 175, to record control spots on the film frame, at those particular times, when circuits are completed through the emitter device 59, and data storage devices SR8 and SR9.

After a predetermined number of film frames have been reproduced, to correspond to the predetermined number sensed on the card from which the reproduced data was sensed, relay R16 is energized to wipe out the control data and amount data stored in relays SR1u, SR1t, SR8 and SR9, and condition automatically other circuits, so that the data can be reproduced from the next card, and reproduce as many film frames as indicated on the said card by the control data disposed thereon.

Assume, that the control data set up in relays SR4u and SR4t is equal to fifteen, indicating that fifteen film records, or frames, are to be reproduced, in accordance with the data stored in relays SR8 and SR9. When the tenth film frame is reproduced, the magnet MA4u is operated, to advance the conducting arm SA4u, to close the contacts TC4u to enter one into the tens order relay SR4t by the following circuit: conductor 250, magnet MA4t, contacts TC4u and conductor 251, energizing the magnet, which when deenergized (upon reset of relay SR4u) effects advancement of conducting arm SA4t to the contact 1 of the group of contacts CT4t, thereby representing the number ten. Closure of contacts TC4u also completes a circuit from conductor 250 to contacts C8, magnet MR4u, contacts R16c, and TC4u to conductor 251, energizing the said magnet net, to effect resetting of arm SA4u, to the normal position shown in Fig. 12b, to engage the first contact of the group CT4u, and to unlatch the contacts TC4u. The arm SA4u is now again advanced, step by step, for each film frame reproduced, until the said arm engages the contact

5 of the group, whereupon, a circuit is completed as follows, near the end of the cycle: conductor 250, arm SA4t, contacts 1 of the groups CT4t and CT1t, arm SA1t, contact 1 of group CT1t, arms SA1t and SA1u contact 1 of the group CT1u, arm SA1u, contacts 5 of groups CT1u and CT4u, arm SA4u, coil of relay R16, contacts R12g, and contacts C7 to conductor 251, energizing the said relay for a brief period in the said cycle. Upon closure of the contacts F1, the reset magnets of relays SR4u and SR4t, SR8 and SR9 are energized by the following circuits: conductor 250 to contacts C8, magnet MR4u, contacts R16b and R16d, switch S8 and contacts F7 to conductor 251, energizing the said magnet; conductor 250 to magnet MR4t, conductor 197, contacts R16d, switch S8, and contacts F7 to conductor 251, energizing said magnet; conductor 250 to magnets MR8 and MR9, conductor 197, contacts R16d, switch S8, and contacts F7 to conductor 251, energizing said magnets; conductor 250 to magnet MR1u, contact 1 of the group CT8u, arm SA8u, contacts R16d, switch S8, contacts F7 to conductor 251, energizing said magnet; conductor 250 to magnet MR1t, contact 1 of group CT8t, arm SA8t, conductor 197, contacts R16d, switch S8, contacts F7 to conductor 251, energizing said magnet. Energization of the said magnets, causes the conducting arms of the relays SR4u, SR4t, SR8, SR9, SR1u and SR1t to be returned to normal position, to engage the first contacts of the respective groups of associated contacts, thus, wiping out the data set up in the said relays. While the resetting of the said conducting arms is effected, a holding circuit for relay R16 is provided, extending from conductor 250 to contacts R16f, coil of the said relay, contacts R16a and C7 to conductor 251. Thus, relay R16 is maintained energized during the said resetting operations. In addition there- 40 to, the following circuits are completed to energize the advance magnets of relays MA8u, MA8t, MA1u and MA1t; conductor 250, magnets MA8u, MA1u, MA8t and MA1t, common conductor 197, contacts R16d, switch S8, and contacts F7 to 45 conductor 251, energizing said magnets, which when deenergized, upon the opening of contacts R16d, cause the corresponding arms SA8u, SA1u, SA8t and SA1t to engage the second contacts of the associated groups contacts, thus selecting the 50 second group of control data storing devices, namely, relays SR2u and SR2t.

Near the end of the cycle, during which relay R16 is energized, relay R12 is deenergized, due to contacts C5 being opened, at this time, to break 55 the holding circuit for relay R12. Relay R12 remains deenergized less than one cycle, until contacts C5 are again closed during the following cycle, however, during the timed interval relay R12 is deenergized, magnets 20 are energized, due 60 to closure of contacts R12b, to cause the card feeding mechanism to be operated, during one cycle, to feed the cards, so that the second card is now fed past the main sensing station, and the third card is fed past the auxiliary sensing 65 station.

The amount data on the said second card is sensed, by brushes 116, to energize relays R20 and R21, at differently timed intervals in the sensing cycle, just as described hereinabove. 70 The sensed data is reproduced on the film record, due to energization of the light sources 175, similarly as described hereinabove, and it is remembered, that the sensed data is also entered in the storing relays SR8 and SR9. Further repro- 75

- duction of the data upon the film record is then produced from the data set up in the said storing relays SR8 and SR9. Counting of the individual records, or frames, reproduced upon the film record is effected exactly as described hereinabove, and when the number, entered in the counting relays SR4u and SR4t, corresponds to the control number, entered in the second storing devices SR2u and SR2t, relay R16 is energized to wipe out the data settings in the devices, just referred to, and effect selection of the next storage devices, in which is stored the control number disposed on the card, which is to be sensed next, at the main sensing station.
- 15 The operations of the machine, for each card presented to the auxiliary sensing station, and later presented to the main sensing station are exactly, as set forth hereinabove, for this reason it is believed, that further description for the record card to film record reproduction operations is not necessary with the exception, possibly, that control circuits are provided, to insure continuous automatic operations of the machine, in the event, that cards are presented, to the sensing stations, in which it has been neglected to perforate the control data indicating the number of reproductions that are to be produced on the film record. These control circuits are shown in Fig. 12b, and are arranged to enter one digit into the storage devices, which have been selected to retain the control number to be sensed on the card at the auxiliary sensing station. In the event, that a control number is not sensed at the auxiliary sensing station relay R19 (representing the relay connected to the sensing brush 112 which is adapted to sense the units order of the control data) is not energized, thereby permitting a circuit to be completed (during the sensing cycle) from conductor 250 to the magnet MA1u (assuming that relays SR1u and SR1t are the storing devices selected at the particular time the card, failing to have a control number perforated therein, is sensed) contact 1 of the group CT5u, arm SA5u, contacts R19c, R15c, pick-up coil a of relay R17, switch S9 and contacts P1 to conductor 251, energizing the said magnets, and the said relay, and establishing a holding circuit therefor, which is as follows: conductor 250, holding coil b of relay R17, contacts R17a, conductor 198, magnets MA5u and MA5t, switch S12, and contacts P9 to conductor 251, energizing the said magnets, which, upon deenergization, cause the arms SA5u and SA5t to be advanced, to select the next group of control data storing devices. In this manner, one reproduction operation is always effected, and upon completion thereof, the number set up in the storing devices SR1u and SR1t, and the number entered into the counting relays SR4u and SR4t correspond, thereby effecting energization of relay R16 to control the machine in the manner described hereinabove.
- It should be mentioned, that relays SR5u to SR7u, and SR5t to SR7t are provided with individual contacts TC5u to TC7u and TC5t to TC7t, respectively, so that, when the fourth impulses are impressed upon the advance magnets of the said relays, the corresponding transfer contacts are closed, to cause the associated reset magnets of the relays to be energized, thus resetting the conducting arms to the first contacts of the group, for the purposes set forth hereinabove.
- In view of the detailed description just set forth, and since the driving mechanism, feeding mechanisms and control circuits are operated
- and conditioned in the same manner, for reproducing the data sensed upon the film record on the record cards, in the form of perforations, the following brief description is believed to be sufficient. Assume now, that all the control switches S1 to S17 are positioned in the FC position, and that the start key is depressed to close the contacts SK1, long enough to condition the machine for automatic operation. For this description, reference should be made to the circuit diagrams shown in Figs. 12a, 12b and 12d, and in the order named. It will be understood, for this type of operation, whereby the recorded film record is sensed (at the main sensing station), and the sensed data is reproduced, or perforated, on the blank record cards accordingly, that upon feeding the film record to the main sensing station, the record cards must be presented, at that time, at the punching station. As it will be seen, from the description to follow, the film record must be properly positioned in the machine, and two blank frames thereof, are fed to the film sensing station upon starting the machine in operation; of course, it will be evident too, that in the event this is not done, no harmful results are effected with respect to the instant invention, the suggestion is made merely as a practical expedient.
- Upon depression of the start key, the relays R1 and R2 are energized, causing operation of the driving motor 21, and associated gearing by means of operated contacts R1a, and energization of the control magnets 209 and 225, causing operation of the film feeding mechanism and the F cam shaft, as described hereinabove. At this time, cam contacts C4 are closed to energize relay R11, and to establish a holding circuit therefor, through the now closed contacts R11a and cam contacts F5. Thus, it is seen, that upon depression of the start key, the card feed magnet 20 is also energized by the following circuit, from conductor 250 to coils of magnet 20, contacts R11b, normally closed contacts R3d, switch S2, contacts R2b, and contacts C1 to conductor 251, thereby effecting a card feeding operation. Near the end of the first machine cycle, the contacts 110 are operated, by the card fed therewith, to energize relay R3, and cause the contacts R3d to be opened, thus opening the circuit to the feed control magnet 20 for the following machine cycle. This is effected, since contacts R10b are not closed until near the end of the said following cycle, when cam contacts F3 are closed to establish a circuit from conductor 250 to coil of relay R10, contacts R11c and R3f, and contacts F3 to conductor 251, energizing said relay, and establishing a holding circuit therefor, through contacts R10a and cam contacts F4. Therefore, at the beginning of the third cycle, the magnet 20 is again energized, through a circuit from conductor 250 to coil of magnet 20, contacts R10b, contacts R3e, switch S2, contacts R2b, and cam contacts C1 to conductor 251, whereby card feeding operations are effected, and by means of the feed rollers 80 and 81 the first card is now fed, intermittently, past the perforating station.
- Upon properly conditioning the machine with record cards, and a control film record, the contacts 54 and 218, respectively, are operated to energize relays R7 and R8, respectively. Thus, it is seen, that a holding circuit, bridging the holding circuit including contacts C2, is established for relays R1 and R2, by the series circuit arrangement of contacts R2a, R1b, R8b and

R10c, thus establishing continuous operation of the machine.

It should be understood now, that as the different index point positions are advanced to the 5 punching station, the corresponding index point positions on the film record are sensed at the main sensing station, for example, as the "9" index point position on the film record is sensed, the "9" index point positions of the record cards 10 are at the punching station under the perforating plungers. As the differentially positioned control spots on the film record are introduced at the sensing position, the presence of the control spots is effective to modify, or interrupt, the 15 impingement of the light rays from the light sources upon the related photo-cells. It is seen that, by means of switches S16 and S17, all the individual light sources are energized continuously. Whenever no control spots are present 20 at the main sensing station, the light rays are conducted by the quartz rods 177 and 182 therefrom, through the transparency of the film record to the related photocells, thus conditioning the said cells. These light responsive means 25 are connected to any well known type of amplifiers, generally indicated at 260, which in turn are connected to control relays 261. The amplifiers are adjusted so that, when light impinges upon the light responsive means, no current 30 flows in the output circuit thereof, however, when the light rays are interrupted, by the presence of control spots on the film record, the light responsive means and amplifier are conditioned, so as to permit current to flow in the output 35 circuit of the amplifier units, this is a well known expedient in the art and needs no further explanation.

It is understood now, that upon the presence of a control spot at the main film sensing station, 40 the corresponding light responsive means and amplifying means are conditioned, so as to effect energization of the related relays 261, when they, by means of the associated contacts 262, complete circuits through the punch control magnets 45 66 as follows: from conductor 250 to switch S16, punch magnets 66, contacts R13d and R13e, contacts 262, common conductor 263, contacts 51, to conductor 251, energizing the corresponding punch magnets 66. Energization of the said magnets 50 operates the related punch plungers to effect perforation of the record card, at the particular columnar index point positions, corresponding to the index point positions in which the sensed control spots appeared on the film 55 record.

It was mentioned hereinbefore, that the auxiliary film record sensing station comprises the light source 186, quartz rods 188 and 189, and photocells 190. The photocells are connected to 60 the amplifiers 267 (which amplifiers are identical to amplifiers 260 and controlled in the manner as described hereinabove), to control the energization of the relays 266, whenever the control spots representing the control numbers are presented 65 to the said auxiliary sensing station to interrupt the light rays impinged upon the corresponding photocells. The auxiliary sensing station is positioned, with respect to the main film record sensing station, so that the control spots are sensed, 70 prior to the sensing of the data at the main sensing station, and the timing of the operations of the control elements of the machine, for the film record to card reproducing operations, corresponds to the timed operations, described above 75 in detail, in connection with the card to film

record reproducing operations. For this reason, it is believed sufficient to set forth briefly, a résumé of the operations which are effected for the film record to card reproducing operations.

The control numbers, disposed on the film 5 records (indicating the number of cards which are to be reproduced in accordance with the data disposed on the film records) are, sensed at the auxiliary sensing station to control the operation of the relays 268, thereby controlling 10 the operation of the relays R18 and R19, at the differential times, the control spots are sensed. Relays SR1u and SR1t are then controlled to select, successively the control data storing devices, namely SR1u, SR1t representing one group 15 of data storing devices, relays SR2u and SR2t representing the second group, and relays SR3u and SR3t representing the third group. Upon selection of the control data storing devices, the control data sensed on the film records is then 20 entered therein, under control of the contacts R18b, R19b and contacts 160. After entering the sensed control data in the selected storing devices, the data to be reproduced, is sensed at the main sensing station to control the operation 25 of relays 261, which in turn control the operation of relays R20 and R21. Operation of relays R20 and R21, at the differential times the control spots are sensed, controls the entry of the data to be reproduced in the storage devices 30 represented by relays SR8 and SR9. Operation of the relay 261 also is effective to control the timed operation of the punch magnets 66, thereby controlling the times at which the associated punch plungers are actuated to 35 perforate the blank cards. Upon reproduction of the first card of the group of cards to be reproduced, relay R13 is operated to render the data storage devices SR8 and SR9 to be effective to control the punch magnets 66, 40 each cycle, in accordance with the data stored therein. For each card reproduced an entry of one is made in the counting relays SR4u and SR4t. When the number entered, in the last mentioned relays, corresponds to the number set 45 up, in one of the selected control data storing devices (SR1u and SR1t; SR2u and SR2t; SR3u and SR3t), relay R16 is energized to control the resetting operations of the mentioned data storage devices, thus wiping out the data stored 50 therein. The resetting operations, it is remembered, are controlled by contacts R16b, R16d, and contacts P6. Upon operation of relay R16, relays SA6u, SA6t, SA1u, and SA1t are operated to select the next control data storage device. Operation of relay R16 also causes the relay R12 55 to be deenergized, which in turn renders the film feeding mechanism operative, for a machine cycle, to present the next film records to the auxiliary and main sensing stations, to repeat the operations, just set forth in accordance with data disposed thereon.

While there has been shown and described and pointed out the fundamental novel features of the invention as applied to a single modification 65 it will be understood that various omissions and substitutions and changes in the form and details of the device illustrated and in its operation may be made by those skilled in the art without departing from the spirit of the invention. It is the intention, therefore, to be limited only as indicated by the scope of the following claims.

What is claimed is:

1. In a record reproducing machine controlled by pattern records containing data to be repro- 75

duced on blank records and a control number for determining the number of record copies reproduced, two groups of record sensing and related recording means for sensing and recording on the records, respectively, the sensing means of each group comprising individual means for sensing the data and control number, individual means for feeding blank or pattern records to the sensing and recording means of each group, means for operating the said individual feeding means, in synchronism, so that the records are presented to the respective sensing and recording means in a predetermined time relationship, means for alternately connecting the data sensing means, of the said groups, to the related recording means, of the said groups, for alternately reproducing the data upon the blank records presented thereto, in accordance with the data sensed upon the pattern records presented to the said connected sensing means, additional means for controlling the connected recording means for reproducing a predetermined number of record copies in accordance with the data sensed upon a single pattern record, and means controlled by the control number sensing means, corresponding to the said connected data sensing means, for controlling the said additional means whereby the number of record copies reproduced is equal to the control number sensed.

2. In a record reproducing machine controlled by pattern records containing data to be reproduced on blank records and a control number for determining the number of record copies reproduced, two groups of record sensing and related recording means for sensing and recording on the records, respectively, the sensing means of each group comprising individual means for sensing the data and control number, individual means for feeding blank or pattern records to the sensing and recording means of each group, means for operating the said individual feeding means, in synchronism, so that the records are presented to the respective sensing and recording means in a predetermined time relationship, means for alternately connecting the data sensing means, of the said groups, to the related recording means, of the said groups, for alternately reproducing the data upon the blank records presented thereto, in accordance with the data sensed upon the pattern records presented to the said connected sensing means, storing means controlled by the connected sensing means for storing the sensed data, additional means for controlling the connected recording means for reproducing a predetermined number of record copies in accordance with the data sensed upon a single pattern record, means controlled by the corresponding control number sensing means for controlling the said additional means, whereby the number of record copies reproduced corresponds to the control number sensed, and means for controlling the recording means by the storing means for reproducing the second and following copies in accordance with the data stored therein.

3. In a record reproducing machine controlled by pattern records containing data to be reproduced on blank records and a control number for determining the number of record copies reproduced, two groups of record sensing and related recording means for sensing and recording on the records, respectively, the sensing means of each group comprising individual means for sensing the data and control number, individual means for feeding blank or pattern records to the sensing and recording means of each group, means for operating the said individual feeding means, in synchronism, so that the records are presented to the respective sensing and recording means in a predetermined time relationship, means for alternately connecting the data sensing means, of the said groups, to the related recording means, of the said groups, for alternately reproducing the data upon the blank records presented thereto, in accordance with the data sensed upon the pattern records presented to the said connected sensing means, storing means controlled by the connected sensing means for storing the sensed data, additional means for controlling the connected recording means for reproducing a predetermined number of record copies in accordance with the data sensed upon a single pattern record, means controlled by the corresponding control number sensing means for controlling the said additional means, whereby the number of record copies reproduced corresponds to the control number sensed, and means for controlling the recording means by the storing means for reproducing the second and following copies in accordance with the data stored therein.

ords to the sensing and recording means of each group, means for operating the said individual feeding means, in synchronism, so that the records are presented to the respective sensing and recording means in a predetermined time relationship, means for alternately controlling the recording means, of the said groups, by the related data sensing means, of the other said groups, for reproducing the data upon the blank records, in accordance with the sensed data on the pattern records, storing means controlled by the data sensing means for storing the sensed data, storing means controlled by the corresponding control data sensing means for storing the control number, means for rendering the data stored therein after reproduction of the first record copy, means for counting the number of record copies reproduced, and means for interrupting further recording operations when the number counted by the counting means corresponds to the stored control number.

4. The invention set forth in claim 3 in which the said storing means comprise relay means.

5. In a record reproducing machine controlled by pattern records containing data to be reproduced on blank photographic film records and a control number for determining the number of record copies reproduced, record card sensing means and photographic film record recording means, the said sensing means comprising individual means for sensing the data and control number, means for feeding pattern record cards to the sensing means, means for feeding blank photographic film records to the said film recording means, means for operating the said individual feeding means, in synchronism, so that the records are presented to the respective sensing and recording means in a predetermined time relationship, means for connecting the record card data sensing means to the photographic film record recording means for reproducing the data upon the film records, in accordance with the data sensed upon the pattern cards, additional means for controlling the recording means for reproducing a predetermined number of record copies in accordance with the data sensed upon a single pattern card, and means controlled by the control number sensing means for controlling the said additional means, whereby the number of record copies reproduced corresponds to the control number sensed.

6. In a record reproducing machine controlled by pattern records containing data to be reproduced on blank photographic film records and a control number for determining the number of record copies reproduced, record card sensing means and photographic film record recording means, the said sensing means comprising individual means for sensing the data and control number, means for feeding pattern record cards to the sensing means, means for feeding blank photographic film records to the said film recording means, means for operating the said feeding means, in synchronism, so that the records are presented to the respective sensing and recording means in a predetermined time relationship, means for connecting the record card data sensing means to the photographic film record recording means for reproducing the data upon the film record in accordance with the data sensed upon the pattern cards, storing means controlled by the data sensing means for storing the sensed data, additional means for controlling the record-

ing means for reproducing a predetermined number of record copies in accordance with the data sensed upon a single pattern card, means controlled by the control number sensing means for controlling the said additional means, whereby the number of record copies reproduced corresponds to the control number sensed, and means for controlling the recording means by the storing means for reproducing the second and following 10 copies in accordance with the data stored therein.

7. In a record reproducing machine controlled by pattern records containing data to be reproduced on blank photographic film records and a control number for determining the number of record copies reproduced, record card sensing means and photographic film record recording means, the said sensing means comprising individual means for sensing the data and control number, means for feeding pattern record cards to the sensing means, means for feeding blank photographic film records to the said film recording means, means for operating the said individual feeding means, in synchronism, so that the records are presented to the respective sensing and recording means in a predetermined time relationship, means for controlling the recording means by the data sensing means for reproducing the data upon the blank film records in accordance with the data sensed on the pattern cards, storing means controlled by the data sensing means for storing the sensed data, storing means controlled by the control number sensing means for storing the control number, means for rendering the data storing means effective for controlling the recording means, in accordance with the data stored therein after the reproduction of the first film record copy, means for counting the number of record copies reproduced, and means for interrupting further recording operations when the number counted by the counting means corresponds to the stored control number.

8. The invention set forth in claim 7 in which the storing means comprise relay means.

9. In a record reproducing machine controlled by pattern photographic film records containing data to be reproduced on blank record cards and a control number for determining the number of record copies reproduced, photographic film record sensing means and record card recording means, the said sensing means comprising individual means for sensing the data and control number, means for feeding pattern film records to the sensing means, means for feeding blank record cards to the recording means, means for operating the said individual feeding means, in synchronism, so that the records are presented to the respective sensing and recording means in a predetermined relationship, means for connecting the film record data sensing means to the record card recording means for reproducing the data upon the cards in accordance with the data sensed upon the pattern film records, additional means for controlling the recording means for reproducing a predetermined number of record copies in accordance with the data sensed upon a single pattern card, and means controlled by the control number sensing means for controlling the said additional means whereby the number of record cards reproduced corresponds to the control number sensed.

10. In a record reproducing machine controlled by pattern photographic film records containing data to be reproduced on blank record cards and a control number for determining the number of record copies reproduced, photographic film record sensing means and record card recording means, the said sensing means comprising individual means for sensing the data and control number, means for feeding pattern film records to the sensing means, means for feeding blank record cards to the recording means, means for operating the said feeding means, in synchronism, so that the records are presented to the respective sensing and recording means in a predetermined time relationship, means for connecting the film record data sensing means to the record card recording means for reproducing the data upon the cards in accordance with the data sensed on the film records, storing means controlled by the data sensing means, for storing the sensed data, additional means for controlling the recording means for reproducing a predetermined number of record cards in accordance with the data sensed upon a single pattern film record, means controlled by the control number sensing means for controlling the said additional means whereby the number of record cards reproduced corresponds to the control number sensed, and means for controlling the recording means by the storing means for reproducing the second and following record cards in accordance with the data stored therein.

11. In a record reproducing machine controlled by pattern photographic film records containing data to be reproduced on blank record cards and a control number for determining the number of record copies reproduced, photographic film record sensing means and record card recording means, the said sensing means comprising individual means for sensing the data and control number, means for feeding pattern film records to the sensing means, means for feeding blank record cards to the recording means, means for operating the said feeding means, in synchronism, so that the records are presented to the respective sensing and recording means in a predetermined time relationship, means for controlling the recording means by the data sensing means for reproducing the data upon the blank record cards in accordance with the data sensed on the pattern records, storing means controlled by the data sensing means for storing the sensed data, storing means controlled by the control number sensing means for storing the control number, means for rendering the data storing means effective for controlling the recording means, in accordance with the data stored therein, after the reproduction of the first record card, means for counting the number of record cards reproduced, and means for interrupting further recording operations when the number counted by the counting means corresponds to the stored control number.

12. The invention set forth in claim 11 in which the storing means comprise relay means.

13. The invention set forth in claim 11 in which the record card recording means comprises perforating means.
